POLISHING MACHINE

Clyde T. MacLean, Detroit, Mich., assignor to
 Motor Products Corporation, Detroit, Mich., a
 corporation of New York

Application May 27, 1936, Serial No. 82,124

4 Claims. (Cl. 51—136)

This invention relates to polishing machines and more specifically to a machine designed to polish the surface of moldings of the type used in finishes for automobiles. Some of the moldings employed in motor vehicle construction are irregular in form, those used for finishing windows, in particular, having a closed form in which the sides thereof are not always in parallel relation with each other. It is in connection with 5 moldings of the latter type that the present invention is particularly applicable, the machine forming the subject matter thereof being designed to facilitate the polishing of the exposed surface of the molding and permit the entire 10 surface to be polished in a single operation.

The following description pertains to a machine for polishing window moldings and the accompanying drawings illustrate a preferred embodiment of the invention.

20 In the drawings:

Fig. 1 is a plan view of the machine;

Fig. 2 is a sectional view taken on line 2—2 of Fig. 1;

Fig. 3 is a section taken on line 3—3 of Fig. 1; 25 and

Fig. 4 is a perspective view of one of the brackets with a polishing pad supported thereon.

Referring to the drawings, it will be seen that 30 a base 10, having T-slots 11 therein, supports a plurality of brackets 12 in which are journaled shafts 13 having sprockets 14 secured thereon. One of the shafts extends through base 10 and is coupled with motor 15 which drives the shaft and the sprockets thereon. Shafts 13 are journaled in suitable anti-friction bearings shown at

35 16. Each of the sprocket shaft brackets is slotted, as indicated at 17, and bolts 18, each having a head 19, cooperate with T-slots 11. A nut 21 on each bolt secures the bracket to 40 the base. It is obvious that, with the connection just referred to, the brackets may be adjusted with respect to the base and to each other. In the form of the invention shown in the drawings the machine is intended to polish an article

45 having sides disposed in several planes, such as the four-sided molding used in the rear quarter window opening in an automobile. Since the outline of the molding is not rectangular, the shaft brackets are positioned at the approximate 50 corners of the inner perimeter of the molding.

Adapted to be driven by and mesh with the several sprockets are a pair of spaced traveling elements shown as endless chains 22, certain links 23 of which are fastened in any appropriate manner to a number of brackets 24. Each of these

brackets comprises a vertical standard 25 to which is secured a substantially V-shaped pad supporting member 26 having apertures 27 adjacent each end thereof. Polishing pads 28 are held in brackets 24 by suitable securing means 29 cooperating with apertures 27 to hold them in place on the brackets. It will be noted that pads 28, when fastened to the brackets, lie partly within the angle formed between the legs 31 of the supporting members 26, thus permitting some latitude of flexibility and adaptability to conform themselves to the cross-sectional contour of the article being polished. In Fig. 2 it will be seen that the surface 32 of the molding, indicated at 33, which is to be rubbed is substantially J-shaped. The pads, which in the present instance are flexible fabric bags filled with a spongy or resilient material, readily adapt themselves to the shape of that surface of the molding which is to be exposed.

Interposed between shaft brackets 12 are a number of guide supporting brackets 34, each of which is substantially L-shaped and has a slotted base 35 to permit adjustment of the bracket with respect to the base 10, in much the same manner as the shaft brackets are adjusted. Each bracket carries a pair of guide rails 36 having a form corresponding with the side of the molding to which it is opposed. Thus the guides assume a parallel position with respect to the sides of the molding, guiding the chain in a predetermined path corresponding with the inner perimeter of the molding to effectively hold the pads in engaging relation with the entire surface of the molding.

The operation of the machine will be understood from the foregoing description. It is only necessary for the operator to position the molding over the polishing elements and by holding the molding firmly against the pads, it will be seen that the entire surface is polished as the pads pass thereover. Thus the entire surface of the molding is polished in one operation, which takes but a short time and lessens the labor and expense in connection with the polishing of articles of the type referred to.

It is obvious that the machine just described is susceptible of changes in size and shape so that it is adapted to use in the polishing of various sizes and forms of molding or similar articles. The chains may be lengthened or shortened, depending on the size of the article to be polished, and pads and supports therefor added to or removed from the chains whenever necessary. The adjustability of the brackets supporting the drive

- shafts and guide pieces permits the establishment of a variety of paths of chain travel so that the machine may be employed for shapes other than that shown in the drawings. The polishing pads 5 illustrated are of the type suitable for moldings of the character shown but they may be replaced by other polishing elements or even by abrading and finishing members, depending on the type of work for which the machine is employed.
- 10 10. What I claim as my invention is:
1. In a machine for polishing the surface of an article having a closed form, an endless traveling element disposed wholly within the perimeter of the said surface, means for driving said element 15 in a path conforming to the perimeter of said surface of the article, a plurality of flexible polishing elements and means on said traveling element for supporting the ends of said polishing elements with the intermediate portions thereof free to flex 20 to conform to the surface of the article.
  2. In a machine for polishing the surface of an article having a closed form, an endless traveling element disposed wholly within the perimeter of said surface of the article, means for driving said element in a path conforming to the perimeter of said surface, a plurality of flexible polishing elements, and a plurality of brackets carried by said 25

traveling element, each of said polishing elements having its opposite ends supported by one of said brackets and having its intermediate portion unsupported to allow bending thereof to conform to the cross-sectional contour of the article. 5

3. In a polishing machine, a base, a plurality of brackets mounted on said base, an endless chain, a plurality of sprocket wheels engageable with said chain and journaled in said brackets, means for adjusting said brackets relative to the base to 10 vary the path of travel of said chain to conform to the shape of an article, and a plurality of flexible polishing elements supported on said chain for engagement with said article.

4. In a polishing machine, a base, a plurality of 15 brackets mounted on said base, an endless chain, a plurality of sprocket wheels engageable with said chain and journaled in said brackets, means for adjusting said brackets relative to the base to vary the path of travel of said chain to conform 20 to the shape of an article, guide members adjustably mounted on the base for engagement with said chain at points intermediate said sprocket wheels, and a plurality of flexible polishing elements supported on said chain for engage- 25 ment with said article.

CLYDE T. MACLEAN.
